EUGENE F. CLARK, OF LEAKSVILLE, NORTH CAROLINA, ASSIGNOR TO MARSHALL FIELD MILLS CORPORATION, OF PHILADELPHIA, PENNSYLVANIA, A CORPORATION OF PENNSYLVANIA.

LOOM FOR WEAVING TUFTED-PILE FABRICS.

Application filed August 19, 1925. Serial No. 51,121.

This invention relates to looms for weaving tufted pile fabric and in particular to that class thereof wherein tuft yarn carriers, commonly called tube frames, are 5 mounted in spaced parallel relation on a pair of endless carrying chains and are successively brought into an operative position to deliver the tuft yarns to a row of yarn grippers to be received by them. In 10 looms of this class, the tuft yarn carriers are each provided with a spool on which are wound a number of tuft yarn strands the colors of which may be varied in accordance with a desired pattern in the product 15 of the loom; and, as each tuft yarn carrier is brought into the operative or yarn delivering position, it presents a row of downwardly directed end portions of its tuft yarn strands, the grippers grasp the strands 20 and draw them downwardly, a cutting device cuts the downwardly drawn strands and the grippers transfer the cut off lengths to the fell of the fabric into which they are woven as pile tufts. 25 An object of my invention is to provide a novel and efficient means for positioning the downwardly directed end portions of the tuft yarn strands with respect to the yarn grippers to ensure the proper operation 30 of the grippers upon the strands in receiving them from the yarn carriers.

Another object of the invention is to provide a cutting device of novel and efficient construction for cutting the lengths of tuft 35 yarns drawn from the carriers by the grippers in which the parts are arranged and actuated rearwardly of the zone of the yarn strands when they extend between the yarn carriers and the grippers prior to the cutting 40 thereof.

A further object of the invention is to provide a novel and efficient means for accurately positioning the tuft yarn carriers with respect to the yarn grippers after the 45 carriers have been approximately brought into the operative position with respect to the grippers.

With the foregoing and related objects in view, the invention consists of the elements and the combinations of them herein- 50 after described and claimed.

In the accompanying drawings, illustrating the invention:—

Figure 1 is a sectional elevation, partly broken away, of a loom embodying my invention. 55

Figure 2 is an end elevation of a part of the loom, showing a part of the main driving mechanism and a part of the mechanism for operating the yarn grippers. 60

Figure 3 is a sectional detail showing one of the yarn grippers, a part of the yarn positioning means and adjuncts. 65

Figure 4 is a sectional detail showing one of the yarn grippers and adjuncts, the yarn gripper being shown in the lowered position. 70

Figure 5 is a front view of a part of the loom frame and the tuft yarn cutting device and its actuating mechanism. 75

Figure 6 is a front view of one of the tuft yarn carriers, its carrying chains and part of the mechanism for supporting and actuating the chains. 80

Figure 7 is a plan of the yarn cutting device and the yarn positioning device and adjuncts. 85

Figure 8 is a sectional plan of the yarn positioning blades and their carrying bar and several tubular guides of the tuft yarn carrier. 90

Figure 9 is a section through the yarn positioning device, on line 9—9 of Fig. 7. 95

Referring to the drawings, 2 designates the frame of the machine, 3 the breast beam comb, 4 the fabric or product of the loom extending from the comb 3 to and around the usual take-up roller 5, and 6 the warp threads extending rearwardly from the fell of the fabric at the comb 3. 99

Mounted to turn in suitable bearings on one of the end standards of the frame 2 is a driving shaft 7, Fig. 2, provided with a worm 8 and provided also with a pulley 10 by means of which power may be applied to the loom. The worm 8 coacts with a worm wheel 11 on a shaft 12 which extends between and is journaled in suitable bearings in the end standards of the frame 2. This shaft 12 carries a pinion 13 in mesh with a gear wheel 14 on a shaft 15 which also extends between and is journaled in

bearings in the end standards of the loom frame 2.

The end standards of the frame are provided with upwardly extending, overhanging portions 16 supporting bearings which carry a shaft 17 which extends across the upper portion of the loom parallel to the shafts 12 and 15. This shaft 17 is provided with spaced sprocket wheels 18 around which pass two sprocket chains 19 adapted to carry a series of spaced tube frames for carrying tuft yarns, one of which is shown at 20. Only portions of the chains 19 are shown in the drawings. They are, as usual, made endless and are guided and supported by a number of sprocket wheels so that the chains may be periodically advanced a distance equal to the space between two of the tube frames carried thereby to bring them successively into the position, or substantially into the position, occupied by the frame 20. For the purpose of thus advancing the chains 19, the shaft 17 is provided with a ratchet wheel 21 actuated by a pawl 22 carried by an arm 23 which turns loosely on the shaft 17 and which is connected to a rod 24 to be actuated by the usual mechanism of the loom.

The tube frame 20 is of usual form, comprising a long horizontally extending bar 26, Fig. 6, provided with end brackets 27 which are pivoted to the chains 19. The frame 20 is provided with the usual spool 28 upon which are wound tuft yarn strands, the free end portions 29 of which extend from the spool 28 to and through tubular guides 30 which extend downwardly from the bar 26, as shown in Figs. 1, 3 and 6.

The construction and operation of the parts thus far referred to are common and well known to persons skilled in this art, and no detailed description or illustration thereof is deemed necessary herein.

As the successive tube frames like the frame 20 are successively brought into the operative position now occupied by the frame 20, the ends of the tuft yarns 29 projecting downwardly from the bottom of the tubes 30 are grasped by a row of yarn grippers 31 which draw them downwardly through the tubes 30 from the position shown in Fig. 3 to the position shown in Fig. 1, a distance equal to the length of a pile tuft. A cutting device, hereinafter described, then cuts the strands above the grippers, and, thereafter, the grippers 31 lower the cut lengths of strands to the position shown in Fig. 4 to be woven into the fabric in the usual manner.

Each yarn gripper comprises two jaws 32 and 33. The jaws 33 are pivoted on the jaws 32 to move thereon from the open position shown in Fig. 3 to the closed position shown in Fig. 1 and back again. The jaws 32 are fixed on a shaft 34 which is fixedly carried

by arms 35 projecting fixedly from a rockable shaft 36 carried by bearings on the loom frame. One end of the shaft 36 extends outwardly and is provided with a gear wheel 37, Fig. 2, in mesh with a rack 38 on a vertically reciprocable bar 39 which slides in bearings 40 on the loom frame. The bar 39 has a bracket 40 fixed thereon and provided with a roller 41 which rests upon the free end portion of an arm or lever 42 which is pivoted, at 43, on the loom frame. The arm 42 has a block 44 pivoted thereon which rests upon a cam 45 secured on the shaft 15, whereby, when the shaft 15 is rotated, the cam 45 will act to raise and lower the arm 42 and therewith the bar 39 and rack 38, and thereby rock the shaft 36 to raise and lower the yarn grippers 31 to and from the position shown in Fig. 3.

The jaw 33 of each yarn gripper is provided with an arm 46 the free end of which extends between two plates projecting from a shaft 47 which is mounted to rock in the arms 35, whereby, when the shaft 47 is rocked in the arms 35, the grippers 31 will be opened, as shown in Fig. 3, and closed, as shown in Figs. 1 and 4. The shaft 47 is provided with an arm 48 which extends downwardly and rearwardly beneath the shaft 36 and carries a lever 49 which is fulcrumed, at 50, thereon. The upper end of the lever 49 is connected by a spring 51 to the arm 48 above the shaft 47. The shaft 36 is provided with an arm 52 carrying a block 53 having a notch 54 formed therein adapted to be engaged by a tooth 55 on a block 56 carried by the lever 49. When the yarn grippers 31 are open, as shown in Fig. 3, they are held in the open position by the spring 51 holding an adjustable screw 57 carried by the arm 48 up against the shaft 36; and when the grippers 31 are closed, as shown in Figs. 1 and 4, they are held in the closed position by the tooth 55 engaging the notch 54 and the spring 51 holding the block 56 in engagement with the block 53.

The grippers 31 are opened and closed by a horizontally reciprocable bar 57 slideable in a bearing 59 on the loom frame in alignment with the lever 49 and having its rearward end pivoted to the upper end of a lever 60 which is fulcrumed, at 61, on the loom frame. The lower end of the lever 60 is provided with a roller 62 which is held against a cam 63 on the shaft 15 by a spring 64 one end of which is attached to the lever 60 and the other end of which is attached to the loom frame, whereby, when the shaft 15 is rotated, the cam 63 will reciprocate the bar 57. The projection of the bar 57 against the lever 49 when the grippers 31 are open, as shown in Fig. 3, moves the arm 48 and lever 49 to rock the shaft 47 against the action of the spring 51 until the grippers 31 are closed and until the tooth 55 engages

the block 53 in its notch 54, as shown in Fig. 1. The engagement of the tooth 55 with the notch 54 holds the grippers closed until the shaft 36 is rocked to lower the 5 grippers to the position shown in Fig. 4. In this position of the parts, the bar 57 is projected against a screw 65 on the lower end of the lever 49, thereby moving the lever 49 on its fulcrum 50 until the tooth 55 is 10 freed from the notch 54, whereupon the spring 51 operates to open the grippers by returning the arm 48, lever 49 and shaft 47 to the position in which the gripper arms 32 and 33 are open, as shown in Fig. 3. 15 Thus it will be seen that, under the influence of the cam 63, the grippers 31 are closed to grasp the tuft yarns 29 when the grippers are in the raised position shown in Fig. 3, and opened to release the tuft yarns when 20 they are in the lowered position shown in Fig. 4.

The mechanism herein shown and described for opening and closing the grippers and for raising and lowering them alone 25 is not included in my present invention and any suitable mechanism for the same purpose may be substituted for it.

After the chains 19 have brought a tube frame like the carrier 20 approximately into 30 the position shown in Fig. 1, each time a row of pile tufts are inserted into the fabric, the frame is accurately positioned with respect to the yarn grippers 31 by arms 66 and 67 (Figs. 1, 3 and 6) which engage the 35 respective ends of the frame. These arms 66 and 67 project fixedly from a shaft 68 which is carried by and fitted to turn in the lower end of an arm 69 at each 40 end of the loom. Each arm 69 projects fixedly from a rockable shaft 70 carried by bearings on the loom frame 2. The shaft 70 is provided with a rearwardly projecting arm 71 which is connected by a rod 72 to a lever 73 which is fulcrumed, at 74, 45 on the loom frame. The lever 73 is provided with a roller 75 which is held against a cam 76 on the shaft 15 by a spring 77 one end of 50 which is attached to the lever 71 and the other end of which is attached to the loom frame, whereby, when the shaft 15 is rotated, the cam 76 will rock the shaft 70 to move the arms 69 and therewith the shaft 68 and arms 66 and 67 forward and back, for a 55 purpose presently explained. The shaft 68 is provided with a rearwardly projecting arm 78 which is connected by a rod 79 to a lever 80 which is fulcrumed, at 74, on the loom frame. The lever 80 carries a roller 81 which is held against a cam 82 on the 60 shaft 15 by a spring 83 one end of which is attached to the arm 78 and the other end of which is attached to the loom frame, whereby, during the rotation of the shaft 15, the cam 82 will rock the shaft 68 and 65 thereby raise and lower the arms 66 and 67

during their forward and back movements under the influence of the cam 76.

The forward ends of the arms 66 and 67 are beveled, as shown in Fig. 6, to engage the respective ends of the tube frame 20 and 70 accurately position it longitudinally with respect to the yarn grippers 31; and the forward ends of the arms 66 and 67 are each provided with a part 84 extending beneath the adjacent end of the frame 20 and having 75 a socket 85, Fig. 3, formed therein and provided with outwardly flaring sides which receives a projection 86 on the adjacent end of the frame 20, when the arms 66 and 67 are raised, and accurately positions the 80 frame in a forward or back direction with respect to the yarn grippers 31. Now, the contours of the cams 76 and 82 are such that after each tube frame like the frame 20 is brought approximately into the position shown in Fig. 1, the arms 66 and 67

are moved forwardly from a position rearwardly of the position shown in Fig. 1, and, as the forward ends of the arms 66 and 67 reach a position beneath the frame 20, they 90 are raised into engagement therewith. As the arms 66 and 67 are thus raised into engagement with the frame 20, the beveled ends of the arms position the frame longitudinally, and the flaring sides of the sockets 85 position the frame laterally or in a forward or back direction with respect to the yarn grippers 31, so that the lower end of each tube 30 of the frame 20 will be directly over the space between the jaws 32 and 33 of a yarn gripper 31 when the grippers are raised to the position shown in Fig. 3.

After the grippers have taken tuft yarns from the frame 20, the cams 76 and 82 operate to lower the forward ends of the arms 66 and 67 from engagement with the carrier 20 and move them rearwardly away from the path traversed by the frames to permit the next succeeding frame to be brought approximately into the position of the frame 20 for a succeeding tuft yarn delivering operation.

To ensure the entrance of each tuft yarn strand 29 projecting downwardly from the tube 30 of the tube frame 20 into the space between the jaws 32 and 33 of the yarn gripper 31 beneath it before the closing of the grippers, I provide the following mechanism:

Extending parallel to the tube frame 20 and arranged forwardly of the zone of the yarn strands 29 delivered therefrom is a bar 87, Figs. 7 and 9, the respective ends of which are secured to and supported by the rearward ends of arms 88 whose forward ends are pivoted, at 89, to parallel bars 90 which are supported to slide forwardly and rearwardly on tables 91 carried by brackets 92 which are secured to and project from end 130

standards of the loom frame 2. The bars 90 are guided in parallel relationship during their forward and back movements by posts 93 rising from the tables 91 on the respective sides of the bars and connected at their upper ends above the bars by plates 94 which retain the plates upon the tables 91.

The rearward ends of the bars 90 are connected to the forward ends of links 95 whose rearward ends are connected to the upper ends of arms 96 extending upwardly from a rockable shaft 97 the ends of which are mounted to turn in the loom frame 2. The shaft 97 is provided with an arm 98 which is connected by a link 99 to a lever 100 which is fulcrumed, at 101, on the loom frame. The lever 100 carries a roller 102 which rests upon a cam 103 on the shaft 15. The roller 102 is held against the cam 103 by springs 104 acting between pins projecting from the slide bars 90 and pins projecting from side standards of the loom frame 2 and tending to draw the bars 90 rearwardly. It will thus be understood that, during the rotation of the shaft 15, the cam 103 will act to move the bars 90 and therewith the arms 88 and bar 87 rearwardly and forwardly.

The arms 88 and therewith the bar 87 are supported by grooved rollers 105 which are carried by the arms 88 and rest upon cam bars 106 secured upon the tables 91 and extending parallel to the arms 88 and bars 90. Each cam bar 106 is provided with a socket or depressed portion 107 and a relatively long, straight depressed portion 108, separated from the socket 107 by a raised portion 109. When the slide bars 90 are moved rearwardly by the springs 104 under the influence of the cam 103 from the position shown in the drawings, the rollers 105 roll along the straight portions 108 of the cams 106 and over the raised portions 109 and down into the sockets 107, and, when the bars 90 are moved forwardly by the cam 103 against the action of the springs 104, the rollers 105 are moved from the sockets 107 over the raised portions 109 of the cam bars 106 and back to the position shown. Each arm 88 is pressed downwardly, to ensure the engagement of the rollers 105 with cam bars 106 at all times, by a spring 110 which encircles a pin or rod 111 and which acts between the arm 88 and a bracket 112 on the adjacent slide bar 90. The lower end of the pin 111 is pivoted to the arm 88 and the upper end portion thereof extends slidably through the bracket 112.

The bar 87 is provided with a row of yarn positioning blades 113 which extend rearwardly from the bar toward the position occupied by the yarn grippers 31 when they are in the raised position shown in Fig. 3. These blades 113 are arranged with their sides in vertical position and in planes par-

allel to the sides of the yarn grippers 31, and the blades are arranged so that the spaces between them will be aligned with and opposite to the grippers 31 and the spaces between the tubular guides 30 of the tube frame 20 above them for a purpose presently appearing.

The blades 113 are set in transverse grooves 114 cut in the bar 87 and they are retained therein by a rod or wire 115 which is seated in a longitudinal groove 116 in the bar 87 and which extends through notches in the upper edge portions of the blades 113. The rod or wire 115 is held in place by a strip of angle iron 117 which is secured to the forward surface of the bar 87, and which extends over the top of the bar and over the top of the rod or wire 115, as clearly shown in the drawings.

When the yarn grippers 31 are in the raised and open position and the tuft yarn carrier 20 has been accurately positioned above them with its tubular guides 30 directly over the grippers, as shown in Fig. 3, the cam 103 and springs 104 operate to move the bar 87 rearwardly, causing the rollers 105 to ride over the raised portions 109 of the cam lever 106 and enter the cam sockets 107, thereby moving the row of blades 113 rearwardly and raising and lowering them just before they reach the limit of their rearward movement. As the blades 113 are raised during their rearward movement, the free ends of the blades enter the spaces between the tubular guides 30 and reach the position shown in Fig. 3, and, thereafter, as the rollers 105 enter the cam sockets 107, the blades 113 are moved down into the spaces between the yarn grippers 31 and reach the position shown by dotted lines in Fig. 3. As the blades 113 are thus moved to this dotted line position, they engage and move into the open jaws of the grippers 31 any end portions of tuft yarn strands 29 which project from the lower ends of the tubular guides 30 which are not properly within the open jaws of the grippers. While the blades 113 are in this dotted line position, the grippers 31 are closed upon the yarn strands and the blades 113 prevent any of the yarn strands from being accidentally moved from the spaces between the gripper jaws 32 and 33 during the closing thereof. After the grippers 31 have been closed, the cam 103 operates to return the bar 87 and blades 113 to the position shown in Figs. 1, 7 and 9 and to hold them therein while the next succeeding tube frame is brought into position to deliver tuft yarns to the grippers, and while the grippers are being lowered and thereafter returned to the position shown in Fig. 3, as previously described.

The tubular guides 30 of the tube frame 20 are wedge shaped in cross section so that their diverging side walls will form spaces

between the guides having wide entrance openings facing the yarn positioning blades 113 to ensure the entrance of the blades into the spaces between the guides irrespective of any slight irregularities which may occur in the spaced relation of the guides 30, due to the accidental bending thereof when in service or due to other causes; and the width of each slot 114 in the bar 87 is slightly in excess of the thickness of the yarn positioning blade 113 therein, so that, while the walls of the slots 114 retain the blades 113 substantially in parallel relation, or sufficiently so to ensure their entrance into the wide entrances of the openings between the guides 30, the blades 113 may move laterally independently of each other, as they pass entirely through the openings between the guides 30, and accommodate themselves to the narrow portions of such openings at the rearward ends thereof.

Arranged rearwardly of the zone of tuft yarn strands extending between the tubular guides 30 and grippers 31, as shown in Figs.

25 1, 3 and 7, is a horizontally arranged bar 118 which extends parallel to the row of grippers 31 and tubular guides 30. The respective end portions of the bar 118 are slidably supported by brackets 119 which extend inwardly from side standards of the loom frame 2. Secured upon the bar 118 is a longitudinally extending plate 120 the forward portion of which extends forwardly from the bar 118 and toward the tuft yarn strands 29 when they project downwardly from the tubular guides 30. The forward edge portion of the plate is serrated, providing cutting teeth 121 having spaces between them arranged in alinement with said tuft yarn strands 29 to receive the same when the bar 118 and plate 120 are moved forwardly from the position shown in Fig. 3 to the position shown in Fig. 1.

The plate 120 is provided with brackets 45 122 to which the forward ends of links 123 are pivoted. The rearward ends of the links 123 are pivoted to arms 124 which project from a rockable shaft 125 which is mounted to turn in bearings in the loom frame. The shaft 125 is provided with an arm 126 which is connected by a rod or link 127 to a lever 128 which is fulcrumed, at 74, on the loom frame. The lever 128 is provided with a roller 129 which is held in engagement with a cam 130 on the shaft 15 by a spring 131 one end of which is attached to the lever 128 and the other end of which is attached to the loom frame, whereby, during the rotation of the shaft 15, the cam 130 and spring 131 will operate to move the plate 120 and bar 118 secured thereto forward from the position shown in Fig. 3 to the position shown in Fig. 1 and back again at certain intervals, as will be presently explained.

The bar 118 is shaped in cross section as shown in Fig. 3 and it is embraced by a block 132 which is slidably fitted thereto to be guided thereby longitudinally thereof. Secured upon the forward portion of the block 132 is a plate 133 having a cutting tooth 134 projecting forwardly from the forward edge thereof. The tooth 134 is shaped or beveled with respect to the teeth 121 as shown in Fig. 7, and the upper surface of the tooth 134 is fitted to slide in close contact with the lower surfaces of the teeth 121 of the plate 120 when the block 132 and plate 133 are moved longitudinally of the bar 118, whereby, the tuft yarn strands extending between the tubular guides 30 and yarn grippers 31 will be cut or severed by the co-operation of the teeth 121 and tooth 134 when the parts are in the position shown in Fig. 1 and the block 133 is moved to move its tooth 134 along the row or series of teeth 121 by mechanism which I shall now describe:

Attached to a rearwardly extending projection on the block 132 is a cord or cable 135 which extends therefrom in opposite directions longitudinally of the bar 118 and plate 120, as shown in Figs. 5 and 7. The cable 135 extends partially around grooved guiding pulleys 136, 137 and 138, which are journaled on suitable brackets on the loom frame, to a grooved pulley 139 fixed on a shaft 140 which is journaled in brackets or bearings on the loom frame. The cable 135 extends entirely around the pulley 140 and the end portions thereof are secured thereto, at 141, whereby when the shaft 140 and therewith the pulley 139 is turned in the direction indicated by the arrow in Fig. 5, the block 132 carrying the cutting tooth 134 will be moved along the teeth 121 in the direction of the arrow in Fig. 7 from the position there shown, and when the shaft 140 and pulley 139 are turned in the reverse direction the block 132 and tooth 134 will be returned to the position shown in Fig. 7. The shaft 140 is provided with a gear wheel 142 in mesh with the teeth of a rack 143 carried by a bar 144 which is slidably in guiding arms 145 projecting from a vertical bar 146 secured to the loom frame. The bar 144 is provided with a pin 147 which projects into a slot in a lever 148 which is fulcrumed, at 149, on the loom frame. The lever 148 carries a roller 150 which extends into a cam groove in cam body 151 on the shaft 15, whereby, during the rotation of the shaft 15, the bar 144 and rack 143 will be raised and lowered at certain intervals to turn the shaft 140 and pulley 139 in the direction of the arrow in Fig. 7 and in the reverse direction to reciprocate the block 132 and tooth 134 to effect the yarn cutting operation.

The operation of the loom, briefly described is as follows;

After each tube frame of a series thereof like the frame 20 is brought approximately into the position shown in Fig. 1 by the chains 19, the arms 66 and 67 are operated, 5 as previously described, to position the frame accurately with respect to the yarn grippers 31 and the open grippers 31 are raised to the position shown in Fig. 3. In this position of the parts, the yarn posi-
 10 titioning blades 113 are moved rearwardly from the position shown in Fig. 1, first to the position shown by full lines in Fig. 3 and then to the position shown by dot-and-dash lines in Fig. 3, as previously explained, 15 entering the spaces between the tubular tuft yarn guides 30 above the yarn grippers 31 and then moving downwardly between the yarn grippers 31 and moving into the jaws thereof any yarn strand ends projecting 20 from the bottom of the tubular guides 30 which are not properly within the open jaws of the grippers. This done, the shaft 47 is turned to close the grippers 31, while the positioning blades 113 remain in the dot-and-
 25 dash line position shown in Fig. 3, as previously described. After the closing of the grippers 31 they are moved downwardly from the position shown in Fig. 3 to the position shown in Fig. 1, drawing the tuft 30 yarn strands 29 downwardly from the spool 28 and through the tubes 30, they are held in the position shown in Fig. 1 for a short space of time, under the influence of the cam 45. While the grippers remain in the 35 position shown in Fig. 1, the bar 118 carrying the plate 120 and cutter 134 is moved forwardly from the position shown in Fig. 3 to the position shown in Fig. 1, as previously described, and, in this position of the 40 parts, the yarn strands extending between the grippers 31 and tubes 30 are within the spaces between the teeth 121 of the plate 120. The cam 151 now operates to move the block 132 and cutting tooth 134 along the bar 118 45 and plate 120, in a manner to sever or cut the yarn strands, as previously explained, leaving a row of cut pile tufts in the jaws of the yarn grippers. The yarn grippers 31 are then lowered by the operation of the 50 cam 45 to the position shown in Fig. 4 and the cut yarn tufts are released by the grippers 31 and woven into the fabric 4 in the usual manner; whereupon the grippers 31 are raised to the position shown in Fig. 3 55 for a succeeding operation.

I claim as my invention:—

1. In a loom for weaving tufted pile fabric and in combination, means for supporting and guiding tuft yarn strands, yarn grippers for acting upon said strands, means to open and close the grippers, yarn positioning blades, and means for operating the blades to position the strands with respect to the grippers when the grippers are open.
- 60 2. In a loom for weaving tufted pile fab-

ric and in combination, a row of guides for tuft yarn strands, a row of yarn grippers for receiving strands from said guides, means to open and close the grippers, a row of yarn positioning blades, and means to move the blades between the guides and between the grippers to position the strands of said guides with respect to the grippers when the grippers are open.

3. In a loom for weaving tufted pile fabric and in combination, a row of guides for tuft yarn strands, a row of yarn grippers movable to and from a yarn receiving position adjacent to said guides, a row of yarn positioning blades, and means for moving the blades first into spaces between said guides and then into spaces between said grippers.

4. In a loom for weaving tufted pile fabric and in combination, a row of guides for tuft yarn strands, a row of yarn grippers for receiving strands from said guides, a supporting bar carrying a row of yarn positioning blades, and means to move the bar to move the blades carried thereby between the guides and between the grippers to position the strands of said guides with respect to the grippers, said blades being laterally movable on said bar.

5. In a loom for weaving tufted pile fabric and in combination, a row of guides for tuft yarn strands, a row of yarn grippers for receiving strands from said guides, a supporting bar carrying a row of yarn positioning blades, and means to move the bar to move the blades carried thereby between the guides and between the grippers to position the strands of said guides with respect to the grippers, said guides having diverging side walls forming wide entrance openings in the spaces between them for admitting said blades, and said blades being laterally movable on said bar.

6. In a loom for weaving tufted pile fabric and in combination, a row of guides for tuft yarn strands, a row of yarn grippers for receiving strands from said guides, a row of yarn positioning blades, and means to move the blades first in one direction into a position between the guides and then in another direction from between the guides to a position between the grippers.

7. In a loom for weaving tufted pile fabric and in combination, a row of guides for tuft yarn strands, a row of yarn grippers for receiving strands from said guides, a bar carrying a row of yarn positioning blades, arms projecting from the ends of said bar, movable supports to which said arms are pivoted, means to move said supports, and means to move said arms on said supports to move the blades between the guides and between the grippers.

8. In a loom for weaving tufted pile fabric and in combination, a row of guides for

- tuft yarn strands, a row of yarn grippers for receiving strands from said guides, a bar carrying a row of yarn positioning blades, arms projecting from the ends of said bar, movable supports to which said arms are pivoted, cam operated means to move said supports, and means to move said arms on said supports to move the blades between the guides and between the grippers.
9. In a loom for weaving tufted pile fabric and in combination, a row of guides for tuft yarn strands, a row of yarn grippers for receiving strands from said guides, a bar carrying a row of yarn positioning blades, arms projecting from the ends of said bar, movable supports to which said arms are pivoted, means to move said supports, and cams to move said arms on said supports to move the blades between the guides and between the grippers.
10. In a loom for weaving tufted pile fabric and in combination, a row of guides for tuft yarn strands, a row of yarn grippers for receiving strands from said guides, a bar carrying a row of yarn positioning blades, arms projecting from the ends of said bar, movable supports to which said arms are pivoted, cam operated means to move said supports, and cams to move said arms on said supports to move the blades between the guides and between the grippers.
11. A yarn positioning device for looms for weaving tufted pile fabric, comprising a bar provided with a row of yarn positioning blades extending therefrom in spaced, substantially parallel relationship and being capable of independent lateral movement.
12. A yarn positioning device for looms for weaving tufted pile fabric, comprising a bar provided with transverse, parallel grooves, a row of yarn positioning blades within said grooves and extending from said bar, and means to retain the blades within the grooves.
13. A yarn positioning device for looms for weaving tufted pile fabric, comprising a bar provided with transverse, parallel grooves and a longitudinal groove intersecting the transverse grooves, a row of yarn positioning blades within said transverse grooves and extending from said bar and having notches therein alined with said longitudinal groove, a rod seated in said transverse grooves and said notches, and means to hold said rod in place.
14. A yarn positioning device for looms for weaving tufted pile fabric, comprising a bar provided with transverse, parallel grooves, a row of yarn positioning blades within said grooves and extending from said bar, and means to retain the blades within the grooves, said grooves being wider than said blades, permitting independent lateral movement of the blades.
15. A yarn positioning device for looms for weaving tufted pile fabric, comprising a bar provided with transverse, parallel grooves and a longitudinal groove intersecting the transverse grooves, a row of yarn positioning blades within said transverse grooves and extending from said bar and having notches therein alined with said longitudinal groove, a rod seated in said transverse grooves and said notches, and means to hold said rod in place, said transverse grooves being wider than said blades, permitting independent lateral movement of the blades.
16. In a loom for weaving tufted pile fabric and in combination, a horizontally extending tube frame movable into and from an operative position in which it presents a row of downwardly directed end portions of tuft yarn strands, grippers operable to grasp said strands and draw them downwardly from the carrier, a bar arranged rearwardly of the zone of strands extending between the carrier and the grippers, means to slidably support the bar for transverse movement, a cutting device carried by the bar, means to move said bar and said device forwardly into and rearwardly from an operative position, and means to actuate said device when in the operative position to sever said strands.
17. In a loom for weaving tufted pile fabric and in combination, a horizontally extending tube frame movable into and from an operative position in which it presents a row of downwardly directed end portions of tuft yarn strands, grippers operable to grasp said strands and draw them downwardly from the carrier, a bar arranged rearwardly of the zone of strands extending between the carrier and the grippers, means to slidably support the bar for transverse movement, a cutting device carried by the bar, a rotatable cam, a link and lever mechanism connected to said bar and operated by said cam to move the bar and the cutting device forwardly into and rearwardly from an operative position, and means to actuate said device when in the operative position to sever said strands.
18. In a loom for weaving tufted pile fabric and in combination, a horizontally extending tube frame movable into and from an operative position in which it presents a row of downwardly directed end portions of tuft yarn strands, grippers operable to grasp said strands and draw them downwardly from the carrier, a bar arranged rearwardly of the zone of strands extending between the carrier and the grippers, means to slidably support the bar for transverse movement, a cutting device carried by the bar, a lever, a link connecting said lever and said bar, means to operate said lever to move the bar and the cutting device forwardly into and rearwardly from an op-

erative position, and means to actuate said device when in the operative position to sever said strands.

19. In a loom for weaving tufted pile fabric and in combination, a horizontally extending tube frame movable into and from an operative position in which it presents a row of downwardly directed end portions of tuft yarn strands, grippers operable to grasp said strands and draw them downwardly from the carrier, a strand cutting device arranged rearwardly of the zone of strands extending between the carrier and the grippers, means to support and move said device from an inoperative position rearwardly of and spaced from said zone to a cutting position in the region of said zone, and means to actuate said device when in the cutting position to sever said strands.
20. In a loom for weaving tufted pile fabric and in combination, a tube frame, a carrying device pivotally supporting the tuft yarn carrier, grippers operable to grasp and act upon tuft yarn strands carried by said frame, a carrying lever movable on a fixed fulcrum, a positioning lever fulcrumed on the carrying lever and provided with means to engage the tube frame and position it with respect to said grippers when the positioning lever is moved, means for rocking the carrying lever on its fulcrum, and means for moving the positioning lever relatively to the carrying lever into and from engagement with the tube frame.
21. In a loom for weaving tufted pile fabric and in combination, a tube frame, a car-

rying device pivotally supporting the tuft yarn carrier, grippers operable to grasp and act upon tuft yarn strands carried by said frame, a carrying lever movable on a fixed fulcrum, a positioning lever fulcrumed on the carrying lever and provided with means to engage the tube frame and position it with respect to said grippers when the positioning lever is moved, means for rocking the carrying lever on its fulcrum, a rotatable cam, and means operated by said cam to move the positioning lever relatively to the carrying lever into and from engagement with the tube frame.

22. In a loom for weaving tufted pile fabric and in combination, a tube frame, a carrying device pivotally supporting the tuft yarn carrier, grippers operable to grasp and act upon tuft yarn strands carried by said frame, a carrying lever movable on a fixed fulcrum, a positioning lever fulcrumed on the carrying lever and provided with means to engage the tube frame and position it with respect to said grippers when the positioning lever is moved, means for rocking the carrying lever on its fulcrum, a rotatable cam, means operated by said cam, for rocking the carrier on its fulcrum, a second rotatable cam, means operated by said second cam for moving the positioning lever relatively to the carrying lever into and from engagement with the tube frame, and means for rotating said cams.

In testimony whereof I affix my signature hereto.

EUGENE F. CLARK.
